Keuffel & Esser Company, Hoboken, N. J., a
corporation of New Jersey

Original application April 24, 1937, Serial No. 138,759. Divided and this application July 1, 1939, Serial No. 282,549

138,759. Divided and this application July 1, 1939, Serial No. 282,549

aims. (Cl. 33—79)

This invention relates broadly to parallel motion drafting devices of the kind in which the several tools which the draftsman handles most frequently are embodied, in principle, in one unit to obviate the necessity of a draftsman reaching about for a required tool, thereby enabling the draftsman to keep his attention concentrated directly upon the drawing. More particularly the invention relates to so-called anchors for such drafting devices.

Drafting devices of this character have heretofore been proposed in which the adjacent ends of two arms are pivoted together, the free end of one arm being secured to the remote side of a drafting board while the free end of the other arm is provided with a protractor and straight edges which are in fixed angular relation to move about the center of the protractor as an axis. Such straight edges have heretofore been so associated with the protractor as to be set and locked at any angle of the protractor or to be automatically stopped at predetermined intervals. The straight edges of drafting devices of this type have been maintained in the desired relation to the drawing board irrespective of the angularity of the arms by means of endless bands embracing pulleys of the three movable joints of the construction.

This application is a division of United States application Serial No. 138,759 filed April 24, 1937.

It is an object of the invention to provide for an adjustment of one of the pulleys about which one of the endless bands passes whereby the straight edges may be caused to conform to lines already existing on the drawings.

The invention also seeks improved adjustments for the hinge connection at the anchoring point to permit leveling of the instrument with respect to the board.

Yet a further object of the invention is to provide adjustability of the angle of inclination of a fixed pulley with respect to its pivotal axis in a horizontal plane.

The invention also resides in the details of construction by which a drafting device is provided which is practical from the standpoint of ease and convenience in manufacture and durability and facility in use.

These and other objects of the invention and the means for their attainment will be more apparent from the following detailed description, taken in connection with the accompanying drawings illustrating one embodiment by which the invention may be realized, and in which:

Figure 1 is a view showing the drafting device of this invention, in plan;

Figure 2 is a transverse vertical sectional view, taken in the planes indicated by the broken line 2—2 of Figure 1, looking in the direction of the arrows and showing the adjusting means for the fixed pulley at the anchored end.

Figure 3 is a view in elevation of the anchor, taken on the line 3—3 of Figure 1, looking in the direction of the arrows, and showing details of the adjustable pivotal mounting for the fixed pulley brackets; and

Figure 4 is a view, in side elevation, of the mounting at this point and taken in the plane indicated by the line 4—4 of Figure 1, looking in the direction of the arrows.

Referring first to Figure 1, it will be noted that the drafting device of this invention comprises two arms indicated generally at 16 and 18, respectively, whereof the adjacent ends of the respective arms are pivoted as at the point 20. The arm 16 is also pivoted, as at 22, at its free end to a fixed anchor member indicated generally at 24, by which the device is mounted on the drawing board, a fragmentary portion of which drawing board is indicated by the numeral 26. Mounted on the free end of the arm 18, as at 28, is the protractor 30. A knob 32 is turnable relative to the end of the arm 18 about the pivot 30 28 to adjust the position of straight edges 29 with respect thereto.

Each of the arms 16 and 18 consists generally of a pair of spaced channeled shaped connecting members. Between the connecting members of arm 16 is a top wall defining a space therewithin for a so-called fixed pulley 50.

Referring now to the end of the member 16 containing the pulley 50, that is, the end of the arm 16 at the right in Figure 1. This structure is shown as mounted upon an anchor member with provision for movement about a vertical axis, the anchor member being indicated generally by the numeral 24. This anchor member is adapted to be clamped to the remote edge, preferably, of the drafting board 26, as shown in Figure 1, the clamping means being shown in Figure 3. Conveniently, a bracket consisting of a flat surface 63, to rest on the top face of the drawing board, is provided with a downwardly depending positioning wall surface 64 lying in a plane at right angles to the lower surface of the member 63 so that it can be placed on a drawing board and fit with relative accuracy. This bracket is formed at its lowermost portion with threaded bosses 66 through which pass the clamp

screws 67 by which the bracket may be rigidly mounted on the drawing board or drawing table. Such board or table may be firmly clamped between the surface 63 and the heads 68 of the clamp screws.

Above the table member 63 rise two spaced bearing members 70, each formed with a hemispherical recess 71 in a horizontal line. To these bracket members or bearings 70 is pivotally mounted the adjustable arm or plate 73 which 10 pivotally supports the free end of the arm 16. This plate is really a bifurcated member having the spaced arms 74 and 75, Figure 1, formed with pivots as shown in Figure 3.

The pivot in one of the arms, say the arm 75, is shown as a screw 76 with a round point 77 on the axis of the screw adapted to be received in the recess 71 of the anchor member 70 and slotted at the other end, as at 78, to afford adjustment, as by a screw driver, for wear. The screw 76 is fixed in adjusted position by a lock nut 79.

At the other end a threaded pivot member 80 is mounted in the bearing arm 74 by a lock nut 81, the pivot or rounded bearing point 83 being eccentric with respect to the axis of the threaded portion 80 so that the same may be turned, as by the application of a wrench on the nut-like or polygonal portion 82 integral with the screw 80 to change the eccentricity of the rounded point 83, thereby raising or lowering the arm 74 and thereby permitting levelling of the plate 73, it being possible, for instance, as shown in Figure 3, to offset the arm 74 through an angularity indicated, say, by the broken lines A and B of that figure.

The plate 73, Figure 2, which may take any form so long as it has the desired strength and rigidity, is formed at a convenient point remote from the pivot ends 74 and 75 with a central bearing portion 85 receiving races 86 for anti-friction bearings 87 which support the pivot pin 22 about the axis of which arm 16 turns. The fixed pulley 58 turns in adjustment, on a cylindrical surface 90 of the plate 73.

The fixed pulley 58 is provided with a recessed surface 92 to receive the endless band 94 and therebelow has integral with it an arm 96 formed with an elongated arcuate slot 97 concentric with the axis of the pin 22 so that the pulley may be shifted about its axis with respect to the axis of the arm 16. Through the slot 97 passes a locking screw 98 whereby the angular position of the pulley may be adjusted within desired limits for moving the endless bands 94 longitudinally of the arms 16 and 18 for an adjustment which is translated to the straight edges.

With the pivot 22 anchored on an edge of the board and where the board is level, any movement of the protractor to bring the straight edges to any desired working position will vary the angularity between the two arms 16 and 18 but by virtue of the endless band, the straight edges will, in known manner, be maintained at the desired inclination to a fixed line either indicated or imaginary on the drawing.

It will thus be seen that an anchor for a drafting device has been provided which may be readily secured to the back of the drawing table by holding the vertical bearing surface of the anchor against the rear edge of the board and securely tightening the clamp screws. Again the straight edges may be aligned to the base line

of a drawing already made. This is accomplished by inserting a thin adjusting pin in the capstan head clamping screw 98 and releasing the same. Then by taking the knob in one hand and the straight edges in the other, the straight edges may be shifted until they align with a base line of the drawing when the clamp screw 98 is again tightened.

The height of the arms above the board may be adjusted so that the straight edges will lie flat upon the board. By inserting a thin adjusting pin in the capstan head screw 188 Figure 4, turning this screw in one direction lowers the arms toward the board whereas turning it in the opposite direction raises the arms away from the board. Moreover, by releasing the nut 81, the eccentric screw 80 may be rotated by means of a wrench to raise or lower the straight edges from the drawing board. Between these two adjustments, the straight edges can be made to lie flat upon the board, while no part of the arms or knee joints touches the board except the supporting bosses under the control knob.

Various modifications will occur to those skilled in the art in the composition, configuration and disposition of the component elements going to make up the invention as a whole as well as in the selection and combination of selected features to accomplish the results sought, and no limitation is intended by the phraseology of the foregoing description or illustrations in the accompanying drawings except as indicated in the appended claims.

What is claimed is:

1. An anchor for a parallel motion drafting device of the wheel and band type comprising clamping means, a support, means to pivotally mount the support on the clamping means to turn about a horizontal axis, means to vary the relative elevations of the pivoted mounting means with respect to the clamping means comprising an eccentrically mounted pivot, and a spaced adjustable member to position said support with respect to said clamping means.

2. An anchor for a parallel motion drafting device of the wheel and band type comprising clamping means, spaced bearing members formed, respectively, with oppositely facing horizontally aligned recesses, a bifurcated support whereof the arms are spaced a distance greater than the bearing members, said arms being formed, respectively, with horizontally disposed threaded passages, a screw in one passage whereof the end is disposed in the recess of one bearing member, a screw in the other passage, said last named screw being formed with a polygonal portion and an end integral with the polygonal portion, and eccentric to the screw axis, for reception in the recess of the other bearing member, and a spaced adjustable member to position said support with respect to said clamping means.

3. An anchor for a parallel motion drafting device of the wheel and band type comprising a table member adapted to be attached to the surface of a drawing board comprising two bearing members in horizontal axial alignment, a support to carry the arm of a drafting device pivoted to said bearing members on said horizontal axis at two points, one of said points being eccentrically adjustable and a spaced adjustable member engaging said table member for positioning said support with respect to said table member.

CARL W. KEUFFEL.
